JUNCTION BOX

Henry Redfield Thompson, East Falls Church, Va., assignor of one-half to Edward T. Fenwick, East Falls Church, Va.

Application July 20, 1935, Serial No. 32,457

6 Claims. (Cl. 247—21)

This invention relates generally to junction boxes such as are in common use for receiving the ends of wiring in electric systems, adapted to be connected to each other, or to the terminals 5 of a switch mounted therein.

When boxes of this type are used in lath and plaster walls, or in walls formed of fibrous material, it is usually very difficult to secure the junction or switch boxes firmly in position. The 10 main object of the present invention is to eliminate this defect in such junction boxes, and to provide a means by which these boxes may be firmly secured on lath and plaster or fiber board walls.

15 Other objects of the invention will become apparent as the detailed description thereof proceeds.

In the drawing:

Figure 1 is an elevation of a switch box embodying the present invention, the cover plate being broken away to show details of construction;

Figure 2 is an elevation to an enlarged scale of the box shown in Figure 1, with the cover plate removed therefrom;

Figure 3 is a vertical section taken on the line 3—3 of Figure 2;

Figure 4 is a horizontal section taken on the line 4—4 of Figure 3; and

30 Figure 5 is a perspective view of an angle plate forming one of the essential elements of this invention.

As shown in the drawing, the invention comprises a switch box 1 of standard construction, 35 and having its sides and rear wall provided with the usual circular weakened portions 2, adapted to be knocked out to receive the ends of wiring intended to be spliced to each other, either directly, or through the medium of a switch. Boxes 40 of this type have their upper and lower end walls provided with laterally deflected lugs 3 and 4, having screwthreaded apertures 5 and 6, to receive machine screws 7 for the purpose of securing a cover 8, in position.

45 The upper and lower walls 9 and 10 are provided with the usual securing plates 11 and 12, respectively, each of which is provided at its opposite ends with inwardly directed bifurcated arms 13 and 14, (see Figure 4) adjustably mounted on said walls and adapted to be secured in adjusted position with respect to the front edge of the box by means of the set screws 15 tapped into screwthreaded apertures in said upper and lower end walls.

50 55 As so far described, the junction box is stand-

ard and in common use. The adjustment of the securing plates 11 and 12 with respect to the front edge of the box 1 depends upon the thickness of plaster or other finish on the wall where the box is designed for use. In this old form, it is common to use ordinary wood screws for fastening the securing plates 11 and 12 to lath and plaster, or to plugs driven in brick walls. It is not always possible to have the screws encounter wood laths in the common lath and plaster walls, and it is difficult to drive plugs into brick or tile walls where it is necessary to have the screws very close to the edges of the opening intended to receive the junction box. It is practically impossible to secure devices of this type firmly to 15 wallboard which is commonly made of compressed paper or compressed fiber and therefore very ill-adapted to receive and hold the screwthreads of the common wood screws.

To overcome the objections noted above, I 20 have provided the upper and lower end walls with slots 16 and 17 adapted to receive slidably the narrow neck 18 of an angle plate designated generally by the reference numeral 19. This plate 19, on one end of the neck 18, is shaped 25 to form a T-head 20, while the other end of the neck 18 is shaped to provide a comparatively broad plate 21, having screwthreaded apertures 22 and 23 therethrough to receive the screwthreaded shanks of the headed machine screws. 30

It can be readily seen from Figure 3 of the drawing, that in practicing this invention the only change involved in the standard box is that required by the formation of the slots 16 and 17. This change, of course, can be effected with practically no additional cost, since it requires nothing more than a slight addition to the die commonly used for stamping the rear and opposite end walls from sheet metal.

Obviously, the plates 19 can also be stamped 40 very readily from sheet metal; and can be very readily assembled by passing the T-head 20 and neck 18 through the slots 16 and 17 as a preliminary to using the box in connection with a lath and plaster or fiber board wall. In setting 45 the box into the opening, the upper plate 19 will lie flat of its own weight against the upper wall 9. The lower plate can be held flat by the operator engaging the head 20 and holding it in such position until it shall have passed beyond the inner face of the wall W. With the securing plates properly adjusted for the depth of plaster or other finish, it will be evident that the mechanic can readily manipulate the plates 19 toward the rear face of the wall W, in such position as to 50 55

receive the machine screws 24. When this is done, it is evident that it would be practically impossible to jar the box loose from the wall, or even to pull it apart from the wall without practically destroying the wall.

What I claim is:

1. A junction box having securing plates adjustable toward and from the front edge of said box on opposite end walls thereof, said walls being provided with slots extending substantially at right angles to said edge, clamping plates slideable on said walls along said slots toward and from said securing plates, and means extending through said securing plates for adjusting said clamping plates toward said securing plates.
2. A junction box having securing plates adjustable toward and from the front edge of said box on opposite end walls thereof, said walls being provided with slots extending substantially at right angles to said edge, clamping plates slideable on said walls along said slots toward and from said securing plates, and means extending through said securing plates for adjusting said clamping plates toward said securing plates, said clamping plates being rotatable from folded positions against said walls into positions at right angles thereto.
3. A junction box having securing plates adjustable toward and from the front edge of said box on opposite end walls thereof, said walls being provided with slots extending substantially at right angles to said edge, clamping plates slideable on said walls along said slots toward and from said securing plates, means extending through said securing plates for adjusting said clamping plates toward said securing plates, said clamping plates being rotatable from folded positions against said walls into positions at right

angles thereto and having parts extending through said slots to the interior of the box to effect said rotation.

4. A junction box having a securing plate adjustable toward and from the front edge of said box on one wall thereof, said wall being provided with a slot extending substantially at right angles to said edge, a clamping plate slideable on said wall along said slot toward and from said securing plate, and means extending through said securing plate for adjusting said clamping plate toward said securing plate.

5. A junction box having a securing plate adjustable toward and from the front edge of said box on one wall thereof, said wall being provided with a slot extending substantially at right angles to said edge, a clamping plate slideable on said wall along said slot toward and from said securing plate, and means extending through said securing plate for adjusting said clamping plate toward said securing plate, said clamping plate being rotatable from folded position against said wall into a position at right angles thereto.

6. A junction box having a securing plate adjustable toward and from the front edge of said box on one wall thereof, said wall being provided with a slot extending substantially at right angles to said edge, a clamping plate slideable on said wall along said slot toward and from said securing plate, means extending through said securing plate for adjusting said clamping plate toward said securing plate, said clamping plate being rotatable from folded position against said wall into a position at right angles thereto and having a part extending through said slot to the interior of the box to effect said rotation.

HENRY REDFIELD THOMPSON.
